UNITED STATES PATENT OFFICE

2,479,116

HYDRAULICALLY CHECKED ESCAPE REEL

Herman H. Jackson, Long Beach, Calif., assignor
of one-third to Fred E. Lewelling and one-third
to Carl H. De Leske, both of Long Beach, Calif.

Application February 24, 1948, Serial No. 10,246

2 Claims. (Cl. 254—158)

1

This invention relates to a hydraulically checked escape reel for use in buildings, towers, such as oil well towers, and other structures having material height.

My invention permits an occupant or workman of a building or a tower to readily escape from that building or tower by lowering himself on a cable, unspooling of the cable being controlled by a suitable check means such as a hydraulic check or snubber.

An object of my invention is to provide a novel hydraulically checked escape reel which is simple and compact in construction, and which can be readily positioned in a building or on a tower so that an occupant or workman can lower himself to the ground by clinging to a cable which is reeled in the escape device.

Another object of my invention is to provide a device of the character stated in which the cable can be quickly re-reeled after it has been extended in actual use.

Another feature of my invention is to provide a device of the character stated which has a high factor of safety and which is light, compact, and can be easily transported from place to place as desired.

Other objects, advantages and features of invention may appear from the accompanying drawing, the subjoined detailed description and the appended claims.

In the drawing:

Figure 1 is a side elevation of my hydraulically checked escape reel.

Figure 2 is a side elevation of the opposite side from that shown in Figure 1.

Figure 3 is a vertical sectional view of my hydraulically checked escape reel.

Figure 4 is a side view of the crank plate with the cover plate removed.

Figure 5 is a side view of the hydraulic check with the housing removed.

Figure 6 is a transverse sectional view of the assembly shown in Figure 5.

Figure 7 is another transverse sectional view of the structure shown in Figure 5.

Referring more particularly to the drawing, the numeral 1 indicates a frame, which includes spaced side plates 2, and 3. The entire frame 1, is preferably assembled of various plate sections, however, it might be cast or otherwise formed if desired.

A reel 4, includes a shaft 5, and this shaft is journaled in the side plates 2, 3. A cable 6, is mounted on the reel 4, and is coiled in the usual manner. This cable extends out through an

opening 7, in the bottom of the frame 1. A handle 8, is attached to one end of the shaft 5, and this handle rewinds the cable 6, after it has been extended, and the ratchet release to permit this rewinding will be subsequently described.

A crank plate 9, is journaled on the end of the shaft 5, opposite the handle 8, and this crank plate is preferably on the outside of the side plate 2, although the exact position of this crank plate is not material. This crank plate is caused to turn with the shaft 5, when the cable 6, is being unreeled, by the following construction: A ratchet wheel 10, is fixedly secured to the shaft 5. A ratchet or detent 11, is pivotally secured to the crank plate 9, and engages the ratchet wheel 10, in clockwise rotation of this ratchet wheel, as viewed in Figure 4. The usual spring 12, presses the detent into or against the ratchet wheel 10. It will thus be evident that when the cable 6, is being unreeled, the crank plate 9, will also rotate at the same speed as the shaft 5.

When it is desired to rewind the cable 6, the handle 8, is rotated in a direction so that the detent 11, will escape the drive of the ratchet wheel 10, thus permitting the cable to be re-wound on the reel 4. A cover 13, is mounted on the crank plate 9, and includes the ratchet and ratchet wheel assembly. To retard the free unreeeling of the cable 6, I provide a hydraulic check 14, which is fixedly secured to the frame 1, adjacent the reel 4, and preferably the hydraulic check is above the reel, although it is obvious that other positions are also practical.

The hydraulic check 14, is of a usual and well known type, and the detail construction of this check forms no part of this invention. However, to clarify the operation of my device, one hydraulic check of a type which might be used will be described. A housing 15, includes a pair of fixed walls 16, 16, which project inwardly substantially as shown. An oscillating piston 17, is mounted in the housing, and forms the chambers 18, 18, and 19, 19, with the fixed walls, 16. The piston 17, includes a shaft 20, to which an arm 21, is fixedly attached. A link 22, is pivotally secured to the arm 21, and the crank plate 13, and thus it will be evident that as the crank plate rotates, the arm 21, will oscillate the piston 17. Oscillation of the piston 17, will cause the chambers 18, and 19, to alternately contract and enlarge, thus forcing fluid from between the piston 17, and the fixed wall, 16, during the time that the chamber 18, or 19, is contracting in size.

The fluid can flow through escape ports 23, and 24, and will move from the contracting area of

the snubber to the area which is expanding. As briefly stated, this method of restricting the flow of fluid through a snubber is usual and well known in the art, and the particular type of snubber is of no moment in this invention. The purpose of the snubber is to restrict the free rotation of the reel 4, and cause this reel to rotate at a fixed rate of speed, slow enough so that a person clinging to the cable 6, will not be injured when he reaches the ground.

Having described my invention, I claim:

1. A hydraulically checked escape reel, comprising a frame, a reel journaled in said frame, a hydraulic check means, a crank plate connected to said reel, a crank arm on the hydraulic check means, and a link connecting said crank plate and crank arm, a detent on the crank plate, and a ratchet wheel mounted on said reel, said detent lockingly engaging the ratchet wheel in one direction of rotation of said reel.

2. A hydraulically checked escape reel, comprising a frame, a reel journaled in said frame, a cable wound on the reel, a hydraulic check means

fixedly mounted on said frame, a shaft on said reel, a crank plate journaled on the shaft, a ratchet wheel mounted on the shaft, a detent mounted on the crank plate, and engaging the ratchet wheel, whereby the crank plate rotates with said shaft in one direction of rotation of the shaft, a crank arm on the hydraulic check means, and a link pivotally attached to said crank arm and to the crank plate.
